UNITED STATES PATENT OFFICE.

ROBERT E. KIMBALL, OF CLEVELAND, OHIO, ASSIGNOR TO THE CLEVELAND FOLDING MACHINE COMPANY, OF CLEVELAND, OHIO, A CORPORATION OF OHIO.

FOLDING-PLATE FOR PAPER-FOLDING MACHINES.

1,173,193.

Specification of Letters Patent.

Patented Feb. 29, 1916.

Application filed June 22, 1914. Serial No. 846,465.

To all whom it may concern:

Be it known that I, ROBERT E. KIMBALL, a citizen of the United States, residing at Cleveland, in the county of Cuyahoga and 5 State of Ohio, have invented certain new and useful Improvements in Folding-Plates for Paper-Folding Machines, of which the following is a specification.

My invention relates to improvements in 10 folding plates for paper-folding machines, and has for its object the provision of a folding plate which avoids certain imperfections present in prior constructions.

A type of folding plate which is in common use is shown and described in Letters Patent to Johnson, No. 893,629, granted July 21, 1908, wherein the folding plates respectively comprise two spaced grids, between which the paper is passed by co-acting 20 buckling rolls, and checked by an adjustable stop, before being passed between the folding or creasing rolls. So far as I am advised, all such folding plates have hitherto been constructed with bars or grids 25 extending parallel with the line of travel of the paper, and the sides of the frame of the folding plate. It has been found in practice that the corner edges of the folded sheet not infrequently strike or catch upon these 30 grids, as the sheet is passed into the folding plate; particularly with paper which has sufficient body to furnish a tendency to spring or open at the fold, or whenever the corners are bent out of the plane of the 35 sheet. Accordingly, I have devised certain improvements in folding plates, which will overcome this objection and permit the sheet to travel into and out of said plates without catching or striking edgewise against the 40 ribs or bars thereof, to avoid deflecting the paper from its course.

Briefly stated, my improvement consists in positioning the ribs or bars of the folding plate at an angle with the line of travel of 45 the paper therein, and preferably positioning the same divergently at either side of the plate.

My improvements will be better appreciated by making reference to the accompanying sheet of drawings, wherein:—

Figure 1 is a plan view of one member of the folding plate constructed in accordance with my invention. Fig. 2 is a side view of the assembled folding plate, and Fig. 3 55 is a fragmentary cross-sectional view

through two of the ribs and the opposing bars. Fig. 4 shows an enlarged longitudinal section:

Throughout the several figures of the drawing, I have employed the same character of reference to indicate similar parts.

The folding plate comprises upper and lower grids *a*, *b*, which, in practice, may respectively be formed of cast iron and brass castings. These grids are spaced apart sufficiently to permit the ready passage of the paper therebetween, and one or more adjustable stops *c* may be provided for securing the buckling of the paper between the rolls, at the proper point; one of which rolls 70 *d* is shown in position (Fig. 2).

The several bars or ribs of the grids are diagonally positioned with respect to the frame, both above and below, and preferably the said ribs are made divergent from the 75 guiding edge of the folding plate.

Referring to Fig. 1, it will be seen that the frame *d* of the upper member of the folding plate, is rectangular; being provided with peripheral lugs for attaching the co-acting lower member of the folding plate thereto by inserted screws. A plurality of bars and ribs *e*, which are T-shaped in cross-section, as shown in Fig. 3, extend longitudinally of the frame, and the raised or bearing surfaces of said ribs are all inclined to the left, at a small angle with the vertical, as shown in the plan view. The right hand rib *f* and guiding edge of the frame *g*, however, are correspondingly inclined at a divergent angle to the right.

By means of dotted lines, a sheet of paper *h* is indicated in the position of entering the folding frame, and its corners are seen respectively to register with the rib *f* at the 95 guiding edge, and one of the ribs *e*, intermediately positioned in the frame. By means of the lines *i* composed of dots and dashes, the position of the sheet within the frame is indicated at its point of engagement with 100 the stop, just before the buckling of the paper occurs to force its passage between the rolls. The corner edges of the sheet in the last position, are free from both of the ribs, by reason of the fact that said ribs are 105 respectively divergent from the line of travel of the paper. Accordingly, there is no possibility for the edges of the paper to strike against, and be deflected by the ribs of the folding plate, and this is true both of the 110

upper and lower members of said folding plate, by reason of the fact that the bars *j* are similarly positioned at angles with the line of travel of the paper. Thus it is seen
5 that the corner edges of the paper are constantly moving away from the inclined ribs, while the paper is entered within the folding plate, and the sheet passes unimpeded against the stop in any position of adjustment.

10 From the foregoing, it will be appreciated that my improvements contemplate the construction and positioning of the ribs forming the bearing surfaces of a folding plate, so that they are diagonal to the line of travel of the paper. Preferably, the guiding edge of the folding plate and one or more of the adjacent ribs, as desired, are diagonally positioned divergently from the remaining 15 ribs or bars. Such divergent positioning of these ribs may be secured by a corresponding disposition of the entire folding plate, but this arrangement is not as desirable as the one specifically shown and described.

20 25 Having now described the preferred form of my invention, I claim as new and desire to secure by Letters Patent the following:—

30 1. In a folding plate for paper-folding machines, the combination of spaced upper and lower members; one of which comprises a grid having its ribs or bars diagonally positioned with respect to the normal line of travel of the paper within the folding plate, substantially as set forth.

35 2. In a folding plate for folding machines, the combination of spaced upper and lower grids; the said grids having longitudinally positioned ribs or bars disposed angularly with respect to the normal line of 40 travel of the paper within the folding plate, substantially as set forth.

3. In a folding plate for paper-folding machines, the combination of spaced upper and lower members; one of said members

comprising a grid having ribs positioned 45 diagonally with respect to the normal line of travel of the paper within the folding plate, and a guiding edge divergently positioned with respect to said ribs, substantially as set forth.

50 4. In a folding plate for paper-folding machines, the combination of upper and lower grids; the said grids being equipped with a guiding-edge, and having ribs or bars diagonally positioned with respect to 55 the normal line of travel of the paper within the folding plate, and divergent from the guiding edge of said folding plate, substantially as set forth.

5. In a folding plate for paper-folding 60 machines, the combination of spaced upper and lower members of said plate; one of said members comprising a grid having ribs or bearing-surfaces approximately T-shaped in cross-section and positioned diagonally 65 with respect to the normal line of travel of the paper within the folding plate, substantially as set forth.

6. In a folding plate for paper-folding machines, the combination of spaced upper 70 and lower grids; one of said grids having ribs approximately T-shaped in cross-section and positioned diagonally with respect to the normal line of travel of the paper within said folding plate, and a guiding 75 edge divergently positioned with respect to said ribs; the ribs of the opposing grid being diagonally positioned to correspond with the opposing ribs of said first mentioned grid, substantially as set forth.

80 In testimony whereof I do now affix my signature in the presence of two witnesses this eighteenth day of June, A. D., 1914.

ROBERT E. KIMBALL.
